UNITED STATES PATENT OFFICE.

FRED V. WOOSTER, OF BOSTON, MASSACHUSETTS.

DESIGN FOR A CARRIAGE-STEP.

SPECIFICATION forming part of Design No. 16,187, dated July 28, 1885.

Application filed March 23, 1885. Term of patent 14 years.

To all whom it may concern:

Be it known that I, FRED V. WOOSTER, a citizen of the United States, residing at the city of Boston, in the county of Middlesex and State of Massachusetts, have invented and produced a new and original Design for Carriage-Steps, of which the following is a specification, reference being had to the accompanying drawings, forming part thereof.

10 Figure 1 is a top or plan view of my newly-designed step, shown with the pad circular in outline; and Fig. 2 is a like view thereof, but with the pad square in outline, these two views being deemed necessary to fully illustrate my design.

15 The leading feature of my design consists in a raised ornamental bar or bars arranged oblique to the line of the shank of the step, and subdivided into small squares, circles, 20 longitudinal ribs, or other forms, the adjacent surface of the pad having minor ornamentation or relief, if preferred.

A is the pad, and B a portion of the shank.

25 In Fig. 1, two bars, *a*, are shown, one being subdivided into small circles and the other into small squares. The other portion of the surface of the pad in this figure is shown with corrugations or minor bars *b*, of much less relief than the subdivisions of bars *a*.

In Fig. 2 the bar *a* consists of a series of 30 ridges, while upon the surface on one side thereof is a star, *c*, and upon the opposite side a clover leaf, *d*; but such minor ornamentation, as the low-relief corrugations *b* or the star or clover-leaf, may be dispensed with or 35 other minor ornamentations substituted therefor, in combination with the oblique bar, without departing from the essential feature of my design.

I claim—

40 1. The design for a carriage-step, consisting of an ornamental broad band or bands extending diagonally across the step, and composed of an aggregation of small figures in relief, as shown in the accompanying illustrations.

45 2. The design for a carriage-step, consisting of an ornamental band or bands extending diagonally across the step, and composed of an aggregation of small figures in relief and minor 50 ornamentation upon the surface of the step, which extends beyond said oblique band, as shown in the accompanying illustrations.

FRED V. WOOSTER.
